Arome D'Art Diffuser [Jul. 23, 2021] found online [Jul. 23, 2021]—
https://www.pattondesign.com/arome-d-art.**Primary Examiner* — John A Voytek(74) *Attorney, Agent, or Firm* — Ryan Dean; Umberg Zipser LLP(57) **CLAIM**

We claim the ornamental design for a diffuser, as shown and described.

DESCRIPTION

FIG. 1 is a perspective view of a diffuser design with cartridge.

FIG. 2 is a front elevation view of the diffuser of FIG. 1.

FIG. 3 is a back elevation view of the diffuser of FIG. 1.

FIG. 4 is a left side elevation view of the diffuser of FIG. 1.

FIG. 5

is a right side elevation view of the diffuser of FIG. 1.

FIG. 6 is a top plan view of the diffuser of FIG. 1; and, FIG. 7 is a bottom plan view of the diffuser of FIG. 1. The broken lines in the views represents portions of the diffuser which form no part of the claimed design.
